BLASTING CARTRIDGE

Guillaume Weber, Hayange, France, assignor to
 Les Petits-Fils De Francois De Wendel & Cie.,
 Paris, France

Application October 4, 1933, Serial No. 692,063
 In France November 9, 1932

4 Claims. (Cl. 102—6)

A type of cartridge is in current use, in which the explosive substance consists of liquid carbonic acid. However, it is a known fact that at the ordinary temperature, carbonic acid cannot be maintained in the liquid state except when it is compressed. For instance, at the temperature of about 15° C., which is a normal temperature, the compression of the carbonic acid should be effected at about fifty to sixty atmospheres. It is evident that in such conditions, the walls of the cartridge must be particularly strong. Thus the known cartridge has very thick steel walls, which however do not protect it against a premature explosion, as the carbonic acid in the cartridge may be in the state of a highly-compressed gas.

Such a cartridge is expensive, owing to the quantity of metal required and to the machine treatment of the case, which case must also be made in several parts whose assemblage must be gas-tight for the very high pressures above-mentioned.

On the other hand, owing to the thickness of the walls, the cartridge has an outer diameter which exceeds the usual diameter of the mine blast-holes, which is approximately forty millimeters; thus the blast-holes require to be enlarged by the use of special boring machines.

The present invention has for its object a new safety explosive for coal mines which contain fire-damp or dust, for potash mines which may also contain fire-damp, and in a general manner for all other uses. This explosive is characterized by the fact that it consists of carbonic acid in the solidified state.

Due to the solid state, the handling of the carbonic acid is much facilitated, as this can be effected, without inconvenience, at atmospheric pressure, and even at the ordinary temperature, since this solid carbonic acid is merely gasified, and in fact rather slowly. It is possible to place the solid carbonic acid in cases which are not gas-tight and whose walls have but little strength, for instance in bags or tubes of paper, asbestos, etc., whose diameter may naturally be as desired, and is comparable with the usual diameters of the blast-holes.

The invention further relates to a cartridge, which is chiefly characterized by the fact that it comprises, in combination, in a case of any kind which is not gas-tight, and consists for example of paper or asbestos, a charge consisting of solid carbonic acid, and a device of any kind which is adapted to produce a considerable rise of temperature, thus causing the instant gassing of the solid carbonic acid.

This device may consist chiefly of a usual priming cartridge containing liquid oxygen or the like, and preferably of a safety type, which is provided with an igniting device (for instance an electric resistance or a Bickford fuse, with or without a detonator).

The heating device may also consist of an electric resistance.

The invention further relates to methods for the use of solid carbonic acid as an explosive, or of the aforesaid cartridge.

It is feasible, especially, to place in the blast-hole either one or more cartridges, or separately, a cartridge and one or more charges of solid carbonic acid, or several charges of solid carbonic acid separately, by a priming cartridge.

In the accompanying drawings which are given solely by way of example:

Fig. 1 is a lengthwise section of a cartridge according to the invention.

Fig. 2 is a section of a modification.

Fig. 3 is a section of a recipient adapted for the transportation and the preservation of the cartridges.

Figs. 4, 5 and 6 represent methods for using the cartridge and the explosive according to the invention.

In the example represented in Fig. 1, the cartridge comprises a case 1 which consists for example of a tube made of a flexible and insulating substance, for instance an inert material such as asbestos or paper. This tube may be obtained simply by winding upon itself a sheet of paper, asbestos etc. The lower end of the tube is simply folded over at 2 in order to form a bottom which need not be gas-tight, and even the contrary, as this facilitates the exit of small quantities of carbonic acid which may be given off between the time of manufacture and the time of use.

The case 1 is filled with solid carbonic acid 3 up to a certain level *ab*. This carbonic acid 3 may be used in the state of pieces, as shown in Fig. 1 or of snow, as shown in Fig. 2. It is preferable to press down the solid carbonic acid so that it will be well packed, or even compressed.

Above the solid carbonic acid is placed a priming cartridge 4. This may consist of any known material. It may consist of combustible powders (aluminium, sawdust, carbon, etc.) contained in liquid oxygen, or of any other explosive, and preferably of a safety type. The said priming cartridge is contained in a case of little strength 5, made for instance of paper or asbestos, resembling the case 1.

The case 1 is folded at its upper end at 6, upon the priming cartridge 4. A hole 7 is then pierced through the folded end of the case 1 and through the cartridge 4. An igniting device is placed at 5 the bottom of the hole 7. This device, in the example herein represented, consists of a detonator (or a charge of powder) in which is embedded an electric resistance 8 which may be supplied with current by conductors 10. Obviously, the resistance 8 may be replaced by a Bickford fuse. It is also feasible, if desired, and if 10 the nature of the priming cartridge 4 will permit, to use as the igniting device simply an electric resistance 8 or a Bickford fuse.

15 In Fig. 2 is represented a modification, in which the case consists of a metallic tube 1' of a relatively great strength. The priming cartridge is eliminated, and is replaced by a simple electric resistance 11. It is to be noted that this resistance 11 might be embedded in the wall of the tube 1', which latter will then consist of insulating material. The tube 1' is closed by a plug 12, which is maintained for instance by a flange 13 formed on the tube 1'. Holes 14 are provided 20 in the plug 12 to permit the exit of the carbonic acid which is given off between the time of manufacture and the time of use.

25 The operation of the cartridges is as follows. Under the action of the great heat, due to the deflagration of the priming cartridge 4 (Fig. 1), or to the electric resistance, 11 (Fig. 2), the charge 3 of solid carbonic acid is abruptly gasified, thus producing a volume of gas which is five hundred times its own volume. As will be observed, the power of the explosive is quite considerable.

30 For the transportation of the cartridges from the place of manufacture to the place of use, and for their preservation, use will be made of non-conducting recipients, or preferably of recipients 40 (Fig. 3) of any usual type containing liquid oxygen 16 or other liquefied gas at a temperature somewhat near -188° C., for instance, this being much lower than that of solid carbonic acid, which is near -80° C.

45 In order to make use of the cartridge containing solid carbonic acid, an ordinary blast-hole 17 (Fig. 4) is bored.

The cartridge, which is for instance of the type of Fig. 1, is placed at the inner end of the blast-hole, which is then wholly or partially filled with any suitable tamping 18.

50 It is of course feasible to combine the cartridge according to the invention with one or more additional charges of solid carbonic acid. In the example represented in Fig. 5, in the inner end

5 of the blast-hole 17, is placed a small bag 19 containing carbonic acid. The cartridge 1 is then placed in such position that the priming cartridge 4 will be located between the two charges 3 and 3' of solid carbonic acid.

10 In the example represented in Fig. 6, the priming cartridge 4 is independent, and is located between two charges 3' and 3'', each of which consists of one or more small bags of solid carbonic acid.

15 Obviously, the invention is not limited to the aforesaid methods of execution and utilization, which are given solely by way of example.

Having now described my invention what I claim as new and desire to secure by Letters Patent is:

20 1. A blasting cartridge comprising solid carbon dioxide in the form of small pieces, a heating element adapted to produce the heat necessary to cause the instant vaporization of said carbon dioxide, and a flexible and insulating envelope permeable to gas containing said carbon dioxide and said heating element and adapted to allow gaseous carbon dioxide issuing from said solid carbon dioxide to escape out of said envelope.

25 2. A blasting cartridge comprising solid carbon dioxide in the form of snow, a heating element adapted to produce the heat necessary to cause the instant vaporization of said carbon dioxide, and a flexible and insulating envelope permeable 30 to gas containing said carbon dioxide and said heating element and adapted to allow gaseous carbon dioxide issuing from said solid carbon dioxide to escape out of said envelope.

35 3. A blasting cartridge comprising solid carbon dioxide in the form of small pieces, a heating element adapted to produce the heat necessary to cause the instant vaporization of said carbon dioxide, and a flexible and insulating envelope of paper permeable to gas containing said carbon dioxide and said heating element and adapted to allow gaseous carbon dioxide issuing from said solid carbon dioxide to escape out of said envelope.

40 4. A blasting cartridge comprising solid carbon dioxide in the form of small pieces, a heating element adapted to produce the heat necessary to cause the instant vaporization of said carbon dioxide, and a flexible and insulating envelope of asbestos permeable to gas containing said carbon dioxide and said heating element and adapted to allow gaseous carbon dioxide issuing from said solid carbon dioxide to escape out of said envelope.
